MULTICIRCUIT ELECTRIC SAFETY SWITCH

Anton G. Seifried, Akron, Ohio, assignor to The
B. F. Goodrich Company, New York, N. Y., a
corporation of New York

Application November 22, 1950, Serial No. 197,007

7 Claims. (Cl. 200—18)

1

The invention relates to electrical circuit-breaking switches and especially to electrical safety switches suitable for multi-circuit use and suitable for use under conditions where fire is a hazard.

Objects of the invention are to provide an improved electric switch capable of long-life operation and relatively rapid frequency of making and breaking electrical circuits through closed containers or cartridges having electrically conductive flowable material therein; to provide for reliability and safety of operation; to provide for rapidity of cyclical operation; to provide for different circuit connections of the switch; to provide for oscillating the closed containers without movement in translation of the containers; to provide for minimizing localized flexure of looped flexible conductors carried by the assembly; and to provide for simplicity, durability and compactness of construction, convenience of manufacture and servicing, and for effectiveness of operation.

These and other objects and advantages of the invention will be apparent from the following description.

In the accompanying drawings, which form a part of this specification,

Fig. 1 is a plan view of an electric safety switch constructed in accordance with and embodying the invention, parts being broken away,

Fig. 2 is a sectional view in elevation, taken along line 2—2 of Fig. 1, and

Fig. 3 is a perspective view of a rocking platform and cartridge assembly of the switch.

In the embodiment of the invention shown in the drawings, the construction includes a rocking or oscillating structure 10 supporting detachably a plurality of two or more closed containers or cartridges 11, 12 having electrically conductive flowable material therein such, for example, as mercury, such that the axis of oscillation of the structure, indicated by the numeral 13, intersects each of the closed containers at an intermediate region between the ends thereof and preferably, the axis of oscillation intersects the longitudinal axis of each container. By virtue of the intersecting relationship quick tilting of the containers under oscillation about the axis 13 is effected without movement in translation of the containers as a whole, thus facilitating rapidity of making and breaking the electric circuits through the containers.

The rocking structure 10 has an elongated rocking member or platform 14 of stiff material such, for example, as steel or other strong metal plate material having spaced-apart, upturned

2

end portions or flanges 15, 16 interconnected by a substantially flat base portion or seating portion 14a. The end flanges have axially aligned apertures 17, 17 therethrough in alignment with the axis of oscillation 13 providing journal surfaces 56, 57 for receiving bearing pin 54, 55, as shown especially in Figs. 2 and 3, to pivotally mount the rocking member 14 at each end thereof and transversely of a divided protective housing or casing 18 of cast or sheet metal construction. The rocking member including its seating portion 14a is desirably mounted horizontally and substantially parallel to and spaced upwardly from a flat base 19a of the lower part 19 of the casing to facilitate limited rocking movement of the structure 10. The end flanges 15, 16 are spaced from the lower sidewalls of the casing 18 to facilitate also the limited rocking movement.

The rocking member 14 thus provides space at 20 above the seating portion 14a and intermediate the end flanges 15, 16 and extending from side-to-side of the member 14 across the axis of oscillation 13 for receiving the closed containers 11, 12 therein.

The rocking member 14 at its interconnecting web or seating portion 14a disposed between the flanges 15, 16 and desirably below the axis of oscillation 13, carries mounting means or plate 21 of electrical insulating material such, for example, as hard rubber composition or a plastic or other suitable insulating material for supporting the containers such that the axis of oscillation intersects the containers. Preferably, the mounting plate is secured and superimposed in face-to-face relation upon the seating portion 14a. The construction makes feasible an insulated mounting of the plurality or pair of closed containers 11, 12 on the seat thus provided such that they are disposed in spaced-apart insulated relation to the conductive seating portion 14a at axially spaced-apart positions intermediate and spaced from the end flanges 15, 16 and are disposed across the axis of oscillation 13 so as to be intersected by said axis 13 at their intermediate 45 regions and preferably at their longitudinal axes.

Mounting means 22, 22 are provided at positions spaced-apart along the axes 13 for electrically engaging and detachably holding the containers, each means 22 being spaced from and disposed to a side of the axis of oscillation 13, as shown especially in Figs. 1 and 3, so as to embrace an electrically conductive end portion of the closed container. The means 22 includes a base 23 of thin, stiff, electrically conductive metal such, for example, as brass strip material having

an upturned side margin 24 for contacting and registering against an end face of the container. A holding-contactor 25 of spring brass strip material having an upwardly bent, container-receiving end portion construction is superimposed on the base 23 for effecting low-loss electrical contact with and detachably holding and clamping the container in place and for resisting accidental shifting of the container. At the same time, the holding-contactor 25, facilitates conveniently mounting and dismounting the container as for servicing the safety switch. The base strip 23 and the spring contactor 25 are maintained in good electrical contact one to the other and are secured to the rocking member as by one or more screw fasteners 26 of suitable conductive metal threadedly engaging the insulating material of the mounting plate 21 only.

Each pair of means 22, 22 for a container are aligned transversely of the rocking member so that the longitudinal axis of the container extends across the rocking member 14 substantially perpendicular to the direction of the axis of oscillation, and so that the axis of oscillation 13 intersects the container at an intermediate region or approximately its central region. This facilitates quick tilting of the container under oscillation of the rocking member about its axis without movement in translation of the container as a whole, which is advantageous for rapid frequency of making and breaking the electric circuit through the container.

For avoiding interference with an overlying upper part or detachable cover 27 of the housing 18 at the upper limit of rocking movement of the structure 10, the closed container 12 is desirably positioned nearest to and spaced inwardly a short distance from the end flange 16 of the rocking member 14, while the other container 11 is spaced a substantial distance from the container 12 and also from the end flange 15, as shown especially in Figs. 1 and 3.

A T-shaped in section supporting element or terminal block 28 of suitable solid insulating material having spaced-apart apertures in the top or cross bar portion of the T projecting to the sides of the stem of the T, is mounted on and projects upwardly from the mounting plate 21 at the axis of oscillation 13 and between the spaced containers 11, 12, and a second supporting element or terminal block 29 of similar material and construction is mounted similarly with respect to the axis of oscillation but between the container 11 and the other end flange 15 of the rocking member 14. The terminal blocks 28, 29 having their top or cross bar portions uppermost and extending along the axis 13, are secured to the mounting plate 21 only as by suitable screw fasteners (not shown).

For connecting the container 11 to an electric circuit, insulated, electrically conductive wires 30 and 31 are connected to the respective screws 26, 26 of the one pair of means 22, 22 and to a pair of looped conductors 32, 33 of flexible, electrically conductive wire and electrically insulated construction, which wires 30, 31 may be continuations of the end portions of the conductors 32, 33. The conductor 32 has an end portion extending through and secured in one aperture of the top portion of the terminal block 29, which conductor end portion is disposed at the axis of oscillation 13 so as to extend substantially vertical to the seating portion 16a of the rocking member 14 and to pass through the axis of oscillation 13 to promote minimum flexing of the conductor un-

der oscillation of the rocking structure 10. A strain-relief member 34 of coiled, metal spring wire construction is positioned about the end portion of the conductor 32 and extends part way along the conductor, as shown especially in Figs. 1 and 3. The other flexible conductor 33 for the container 11 is similarly extended through and secured in the other aperture of the top portion of the terminal block 29, and has a suitable strain-relief member 34.

The conductors 32, 33 have upwardly looped reaches in spaced-apart, substantially parallel relation to one another, each conductor extending in a single loop from the terminal block 29 at the axis of oscillation 13 and terminating in another end portion extending through and secured to an apertured terminal strip 35 of suitable solid insulating material. The terminal strip 35 extends transversely of the housing 18 at a position spaced substantially to one side of the axis of oscillation to eliminate sharp curvature of the looped reaches of the conductors, and is mounted at its ends upon upwardly extending projections 36, 37 of the base 19a of the housing 18 as by suitable screw fasteners 38, 38.

The other end portions of the conductors 32, 33 having suitable strain-relief members 44, 44 extend through and are secured in spaced-apart apertures of the terminal strip 35, and are electrically connected by suitable insulated wires 39, 40 to spaced-apart bus bars 41, 42 of suitable conductive metal, strip material on the upper surface of the terminal strip, the bus bars being held in place as by suitable screw fasteners 43, 43 which also engage and hold the wires 39, 40, as shown especially in Figs. 1 and 2.

The upwardly looped arrangement of the flexible conductors 32, 33 and their connection to the terminal block 29 at and along the axis of oscillation 13 advantageously accommodates the rocking or oscillating movement of the rocking structure 10 and at the same time, distributes the flexing stresses throughout the entire looped extent of the conductors. This facilitates long service life of the conductors despite relatively rapid frequency of oscillation of the rocking structure 10 and of making and breaking the electric circuit through the closed container 11.

A second pair of suitable flexible conductors 45, 46 for connecting electrically the closed container 12 to suitable spacer-apart bus bars 47, 48 on the terminal strip 35, and having suitable strain-relief members 34, 34 and 44, 44, are constructed and arranged like the flexible conductors 32, 33 and extend likewise in the upwardly looped, spaced-apart, substantially parallel disposition from the apertured top portion of the terminal block 28 at the axis of oscillation 13 to the terminal strip 35.

The bus bars 41, 42, 47, 48 may be connected electrically to the remainder of the electric circuit of which the switch is to be a part by suitable wires (not shown) extending from the bus bars through a suitable aperture (not shown) in the adjacent end wall, for example, of the lower part 19 of the housing 18.

Each closed container may be of like construction; hence only the container 11 will be described in detail. The closed container 11 is desirably of elongated cylindrical form having dimensions such that it can be mounted detachably on the mounting means 22, 22.

The container or cartridge 11 has closed end portions 49, 50 of suitable electrically conductive stiff metal material, one of which portions 50

may be relatively longer than the other for facilitating the alteration of the circuit-closing characteristics of the cartridge according to the particular disposition of the respective end portions to the sides of the axis of oscillation. The closed end portions 49, 50 have their adjacent open end portions maintained in spaced-apart, sealingly attached relation by a short cylindrical spacer 51 of hard rubber insulating material. A suitable quantity of electrically conductive flowable material such, for example, as mercury, is contained permanently in the cartridge 11.

For further protecting the rocking structure 10 against electrical flash-over from the cartridge 12 to the metallic end flange 16, a shield 52 of suitable thin, electrical insulating, sheet material may be secured to the end flange 16 throughout its entire extent. The other end flange 15 of the rocking member 14 is sufficiently remote from the other cartridge 11 of the pair so that the flange 15 does not require a shield of insulating sheet material.

The bearing pins 54, 55 of stiff, wear-resistant steel or other metal for pivotally mounting the rocking structure 10, may be threadedly engaged with interiorly threaded hollow bosses of the sidewalls at the lower part 19 of the housing 18, and project inwardly from the sidewalls in axial alignment one to the other end in alignment with the axis of oscillation 13. The pins 54 and 55 extend into the journal bearings 56 and 57 of the end flanges 15, 16 of the rocking member 14 so that the rocking structure 10 is supported horizontally at a sufficient height above the base 19a of the lower part 19 to permit the desired angular degree of oscillatory movement of the rocking structure 10.

A metal foot pedal 58 mounted at the exterior of the lower part 19, has connected to it a solid shaft 59 of steel or other strong metal material extending through hollow bearing bosses of the sidewalls at the other end of the lower part 19, as shown especially in Figs. 1 and 2. The foot pedal and shaft are preferably separable one from the other and removable from the housing, when desired as for servicing the switch.

An actuator 60 of steel or other suitable metal material is mounted adjustably on the shaft 59 at a position beyond the end flange 15 toward the sidewall of the housing 18 and has an extension 61 projecting radially of the shaft toward the axis of oscillation 13 for carrying at its free end a fixed pin 62 which may be of hardened steel, extending axially toward the end flange 15. The pin 62 is disposed in the space between tines 63, 64 of a forked portion of the end flange 15 to the side of the axis of oscillation 13 nearest the shaft 59. A vertically disposed, coiled metal spring 65 of the compression type between the base 19 of the housing and the extension 61 of the actuator 60 urges the rocking structure 10 to its normally tilted position shown in Fig. 2, and urges the foot pedal to its upper position 75 shown in broken lines in Fig. 2.

The actuator 60 at a position diametrically opposite and axially spaced inwardly from the extension 61 is provided with a relatively short, second extension 66 disposed in the space between adjacent ends of spaced-apart limiting screws 67, 68 threadedly engaging vertically spaced-apart lugs 69, 70 of the lower part 19 of the case, as shown especially in Figs. 1 and 2. Lock nuts 71, 72 on the limiting screws 67, 68 may be provided for maintaining the screws at a desired setting which establishes the desired limits 75

of the range of arcuate movement of the extension 66 and the desired number of degrees of angular movement of the rocking structure for rapidly making and breaking the circuit through the respective cartridges 11, 12.

The protective housing 18 having lower and upper parts 19 and 27 may be of rectangular shape, which parts may have corner bosses 73, 73 with interiorly threaded, aligned openings engageable by suitable hexagon-headed screw fasteners 74, 74 for holding the upper and lower parts in tightly closed relation to resist the entrance of inflammable liquids.

The safety switch described hereinabove may have the bus bars 41, 42 and 47, 48 connected electrically to one or more electrical circuits so that it functions as a two-pole normally open switch with the cartridges disposed as shown, or a two-pole normally closed switch having the cartridges in a reversed disposition relative to that shown, or a one-pole normally open and one-pole normally closed switch having only one of the cartridges in reversed disposition relative to that shown. For example, when the bus bar 42 is connected electrically directly to the bus bar 47, the switch will function as a one-pole double-throw switch having one cartridge reversed for a single circuit, three-wire hookup. With the bus bars and cartridges arranged as shown the switch functions as a double pole, single throw switch for a separate circuit, four-wire hookup. The switch thus makes feasible a plurality of different electrical circuit connections for meeting the requirements of different circuits and usage.

In the operation of the safety switch, assuming the same to be connected to the desired electrical circuit or circuits and the foot pedal 58 in the normal up position at 75 shown in broken lines in Fig. 2, and the rocking structure 10 in the normally tilted condition shown in full lines in Fig. 2, with both mercury-containing cartridges 11, 12 in the normally open circuit condition, for example; the foot pedal 58 is pressed downwardly to the lower position at 76 shown in dot and dash lines in Fig. 2 to rotate the shaft and the actuator 60 and thus compel oscillation of the rocking structure and cartridges through a small degree of angular movement to the position at 77 shown in broken lines in Fig. 2, and against the resistance of the compression spring 65. The mercury in the conductive end portions 49, 49 of the respective cartridges flows across the hard rubber insulator 51 into contact with the conductive end portions 50, 50 of the cartridges thus completing the electrical circuits through both cartridges. Release of the downward pressure on the foot pedal 58 permits the compression spring 65 to compel return movement of the rocking structure about the axis of oscillation to its normally tilted condition thus causing flow of the mercury in the opposite direction until the circuits through the cartridges are broken.

A small degree of angular movement of the rocking structure 13 about the axis of oscillation is all that is required to make and break quickly the electrical circuits through the cartridges and during the angular movement minimum flexure of the looped flexible conductors occurs without objectionable localized flexure of the same. This is advantageous for promoting longer life of the flexible conductors.

Variations may be made without departing from the scope of the invention as it is defined in the following claims.

I claim:

1. A switch for making and breaking electric circuits through a plurality of closed containers having electrically conductive flowable material therein, said switch comprising a rocking platform having a seating portion of generally flat form in the direction along and the direction across said platform disposed generally horizontal and terminating in upturned portions at the ends thereof and having a pivotal mounting at each upturned portion thereof for oscillation of said platform about a generally horizontal axis extending through the space overlying said seating portion between said upturned portions, mounting means carried by said platform at said space for detachably holding the closed containers in said space adjacent said seating portion with the containers in spaced-apart relation along said axis and in a side-by-side disposition across said axis and also for detachably holding the closed containers in said side-by-side disposition with said axis intersecting an intermediate region of each container so that by virtue of such intersection quick simultaneous tilting of all said containers under oscillation of said platform about said axis is effected without movement in translation of the containers as a whole, and flexible conductors carried by said platform for connecting the closed containers to the electric circuits, said flexible conductors being mounted on said platform at said axis and extending upwardly relative to said seating portion each in a single loop for mounting at a position spaced from a side of said platform for accommodating the oscillating movement of said platform about said axis.

2. A switch for making and breaking electric circuits through a plurality of closed containers having electrically conductive flowable material therein, said switch comprising a rocking platform having a seating portion of generally flat form in the direction along and the direction across said platform disposed generally horizontal and terminating in upturned flanges and having a pivotal mounting at each flange thereof for oscillation of said platform about a generally horizontal axis extending through the space overlying said seating portion between said flanges, a supporting element of T-shape in cross-section on said seating portion at the region of said axis having the stem of the T projecting upwardly relative to said seating portion through said space and terminating in apertured cross-bar portions of the T each extending away from a side of said stem in the direction along said axis and spaced substantially from said seating portion, flexible conductors for connecting the closed containers to the electric circuits, said conductors extending through and being secured in the apertures of said cross-bar portions and projecting upwardly therefrom at said axis each in a single loop for mounting at a position spaced from a side of said platform to accommodate the oscillating movement of said platform about said axis, and mounting means carried by said platform and disposed in said space for detachably mounting the closed containers in said space in spaced-apart relation along said axis and in side-by-side disposition across said axis with said axis intersecting an intermediate region of each container so that by virtue of such intersection quick simultaneous tilting of all said containers under oscillation of said platform about said axis is effected without movement in translation of the containers as a whole.

3. A switch for making and breaking electric

circuits through a plurality of closed containers having electrically conductive flowable material therein, said switch comprising a rocking platform for carrying the closed containers and having a seating portion of generally flat form in the direction along and the direction across said platform disposed generally horizontal and terminating in upturned flanges and having a pivotal mounting at each flange thereof for oscillation of said platform about a generally horizontal axis extending through the space overlying said seating portion between said flanges, a supporting element of T-shape in cross-section on said seating portion at the region of said axis with the stem of the T projecting upwardly relative to said seating portion through said space and terminating in cross-bar portions of the T each extending away from a side of said stem in the direction along said axis and spaced substantially from said seating portion and each cross-bar portion having at least an aperture therethrough aligned with said axis, and flexible conductors extending through and secured in the apertures of said cross-bar portions for electrically engaging the closed containers to connect the same to the electric circuits, said flexible conductors extending upwardly in spaced-apart side-by-side relation from said cross-bar portions at said axis each in a single loop for mounting at a position spaced from a side of said platform to accommodate the oscillating movement of said platform about said axis.

4. A switch for making and breaking electric circuits through a pair of cartridges having electrically conductive flowable material therein, said switch comprising an oscillating structure for supporting and imparting oscillating movement simultaneously to said pair of cartridges, said structure comprising a rocking platform of stiff plate material having a seating portion of generally flat form in the direction along and the direction across said platform disposed generally horizontal and terminating in upturned flanges to provide an overlying space between said flanges for receiving the pair of cartridges in side-by-side disposition across a generally horizontal axis of oscillation of the platform and in spaced-apart relation along said axis, means at said flanges for pivotally mounting said structure for oscillation thereof about said axis, a mounting plate of insulating material on a face of said seating portion to provide therewith a seat below said axis for supporting said cartridges in said disposition with said axis intersecting an intermediate region of each cartridge so that by virtue of such intersection quick simultaneous tilting of both cartridges under oscillation of said structure about said axis is effected without movement in translation of the cartridges as a whole, means on said mounting plate at positions spaced-apart along said axis for electrically engaging and detachably holding the pair of cartridges on said seat of the structure in said disposition and said spaced-apart relation, and means including flexible conductors electrically connected to the holding means and disposed on said mounting plate at positions spaced-apart along and aligned with said axis for connecting the cartridges to the electric circuits while accommodating the oscillating movement of said structure.

5. A safety switch for the rapid and frequent making and breaking of electric circuits, said switch comprising a housing having a base, a rocking structure in said housing having a seating portion of generally flat form in the direc-

tion along and the direction across said rocking structure disposed generally horizontal and terminating in upwardly extending end portions to provide an overlying space between said end portions, means at said end portions for supporting said rocking structure pivotally relative to said housing for oscillation of said rocking structure about a generally horizontal axis extending through said space, a mounting plate of insulating material and generally flat form on said seating portion in said space, a pair of cartridges having electrically conductive flowable material therein mounted on said mounting plate in fixed relation thereto at positions spaced-apart along said axis and extending side-by-side across said axis in said space with said axis intersecting each cartridge in an intermediate region thereof so that by virtue of such intersection quick simultaneous tilting of both cartridges about said axis is effected without movement in translation of the cartridges as a whole, pairs of spaced-apart contactor elements of conductive resilient metal material on said mounting plate at said positions of said cartridges for electrically engaging and detachably mounting said cartridges on said seating portion, a terminal block of insulating material having a T-shape in section disposed to a side of each cartridge in alignment with said axis with the stem of the T projecting upwardly from said mounting plate and terminating in cross-bar portions of the T extending from the sides of said stem along said axis, and spaced-apart flexible conductors disposed in pairs and supported by said base of said housing with each pair of conductors extending therefrom to one of the terminal blocks and being electrically connected to a pair of said contactor elements for a cartridge, each flexible conductor extending in a single upstanding loop to one of said cross-bar portions of a terminal block and intersecting the same at said axis for minimizing flexure of the looped conductors under said oscillation of said rocking structure.

6. A switch for making and breaking electric circuits through a plurality of closed containers having electrically conductive flowable material therein, said switch comprising a rocking platform having a base portion of generally flat form in the direction along and the direction across said platform disposed generally horizontal and terminating in outwardly-turned portions at the ends of the platform and said platform having a pivotal mounting at each of the outwardly-turned end portions for oscillation of said platform about a generally horizontal axis extending through the space overlying said base portion between said outwardly-turned end portions, mounting means secured to said base portion and disposed in said space for mounting the closed containers in said space adjacent said base portion with the containers in spaced-apart relation along said axis and in a side-by-side disposition across said axis and also for detachably holding the containers in said spaced-apart relation and in said side-by-

side disposition with said axis intersecting an intermediate region of each container so that by virtue of such intersection quick simultaneous tilting of all the containers under oscillation of said platform is effected without movement in translation of the containers as a whole, and flexible conductors associated with said mounting means for electrical connection with the containers to connect the same to electric circuits and said flexible conductors being mounted on said base portion at said axis and extending outwardly relative to said base portion and to said mounting means each in a single loop for mounting at a position spaced from a side of said platform to accommodate oscillating movement of said platform about said axis.

7. A switch for making and breaking electric circuits through a plurality of closed containers having electrically conductive flowable material therein, said switch comprising a rocking platform having a base portion of generally flat form in the direction along and the direction across said platform disposed generally horizontal and terminating in upturned portions at the ends of the platform and said platform having a pivotal mounting at each upturned portion for oscillation of said platform about a generally horizontal axis extending through the space overlying said base portion between said upturned portions, mounting means including a conductor-supporting element secured to said platform and disposed in said space for mounting the closed containers in said space adjacent said base portion with the containers in spaced-apart relation along said axis and in side-by-side disposition across said axis and also for detachably holding the containers in said spaced-apart relation and in said side-by-side disposition with said axis intersecting an intermediate region of each container so that by virtue of such intersection quick simultaneous tilting of all the containers under oscillation of said platform is effected without movement in translation of the containers as a whole, and flexible conductors associated with said mounting means for electrical connection with the containers to connect the same to electric circuits and said flexible conductors being mounted on said conductor-supporting element at said axis and extending upwardly relative to said base portion and to said conductor-supporting element each in a single loop for mounting at a position spaced from a side of said platform to accommodate oscillating movement of said platform about said axis.
